TUYÈRE CONSTRUCTION FOR UNDERFEED STOKERS

Edward B. Thomas, Middletown, N. Y., assignor, by mesne assignments, to Chrysler Corporation, Highland Park, Mich., a corporation of Delaware

Application December 23, 1944, Serial No. 569,483

2 Claims. (Cl. 110—44)

1

This invention relates to a tuyère construction particularly applicable for use in anthracite burning furnaces having underfeed stokers.

In a tuyère construction of this character it is desirable that it be built up of a series of separate units fitting together and removably supported above and about the retort to provide a support for the solid fuel upwardly therein while admitting air for efficient combustion. It is advantageous both for installation and production to employ a series of unit castings which may be fitted together and assembled for this purpose.

In the burning of anthracite particularly, as well as other kindred solid fuel, it is desirable that the tuyère structure be apertured to permit of sufficient air supply for combustion, but at the same time prevent fine siftings of the fuel from falling through the air openings to build up an obstruction to the free and properly diffused air supply. It is further desirable to so form the tuyère units relative to each other as to baffle the air blast to retard its entry into the fuel and evenly diffuse it about the fire bed to thereby prevent spotty blasts or localized air streams from reaching the fuel. Without such baffled diffusion of the air, and wherein spotty blasts of air may enter the fire bed, clinkers are formed due to such localized excess air. This not only causes inefficient burning of the fuel, but interferes with the consumption of the fuel in fine ashes for convenient or automatic ash removal. For this reason it is desirable that the air supply to the fire bed remain constant and evenly diffused and distributed throughout the entire area of the tuyère. This may only be accomplished wherein the tuyère is so constructed as to prevent the proper distribution of the air by the openings being plugged up from siftings, and wherein the openings are so baffled as to further distribute and diffuse the air so that it enters the fuel bed evenly throughout its entire area to prevent excess air or blast at any localized part of the bed such as to form clinkers.

For the purpose of constructing a tuyère having the advantages of proper combustion and eliminating the disadvantages as above set forth, this invention contemplates the provision of a series of upwardly and outwardly extending bars individually cast to provide an air duct and formed with baffles to distribute the air from the air duct throughout its fire bed supporting portion, suitably supporting said bars in assembled relation and then providing intermittent bar baffles such as to diffuse the distributed air evenly throughout the entire fuel supporting surface,

2

said baffles acting to provide the fuel supporting surface with means to prevent siftings of the fuel from entering the air ducts or plugging the air diffusing openings.

5 In the burning of solid fuel on a tuyère structure of the character herein disclosed, the rate of burning is not uniform over the entire area. It is much faster near the center where the fuel is being fed and decreases toward the outer edges. 10 Therefore, this invention contemplates controlling the admission of air to permit of more air where it is required and less air in those areas where the burning rate is slower.

The full nature of the invention will be understood from the accompanying drawings and the following description and claims:

Fig. 1 is a central vertical section through a retort and tuyère supporting structure showing a portion of a rectangular tuyère in section and 20 a portion in front elevation. Fig. 2 is a section taken on line 2—2 of the upper supporting portion of the tuyère bars with the baffles mounted thereover. Fig. 3 is a section taken on the line 3—3 of the lower portion of the bars with the baffles 25 mounted thereover. Fig. 4 is a perspective view of one of the baffles. Fig. 5 is a perspective view of one of the bars. Fig. 6 is a plan view of the tuyère, parts of which are illustrated in Figs. 1 to 5, inclusive. Fig. 7 is a partial plan view of the 30 modified form of the invention as applied to a circular tuyère structure. Fig. 8 is a central vertical section through substantially one-half of the circular tuyère structure shown in Fig. 7. Fig. 9 is a section taken on the line 9—9 of Fig. 8. Fig. 10 is a perspective view of one of the baffles 35 of the circular tuyère shown in Figs. 7 and 8. Fig. 11 is a perspective view showing the upper portion of the bar of the circular form of tuyère shown in Figs. 7 and 8.

40 In the drawings there is illustrated a tuyère construction embodying, as shown in Fig. 1, a retort 10 into which the solid fuel, such as anthracite, is fed upwardly by a screw feed stoker in the usual manner. Extending outwardly from the 45 retort and either cast integrally therewith or rigidly secured thereto there is provided a tuyère supporting structure comprising a ledge 11, an outer supporting ring 12, all surrounded by a wind box wall 13 formed of refractory material 50 with a supporting ledge 14. The tuyère structure is mounted and supported upon the ledge 11, support 12 and ledge 14 of the wind box wall 13. In the usual manner air is discharged under forced draft into the wind box under the tuyère 55 structure.

The tuyère extends upwardly and outwardly from the retort and within the wall 13 so as to confine the fire bed of the fuel within the lower vertical portion of the tuyère while permitting it to discharge over the upper surface thereof. The structure comprises a series of assembled tuyère bars 15, as shown in Fig. 5, and intermediate baffles 16 illustrated in Fig. 4. Said bars and baffles conform in shape, each bar is provided with a base portion 17 resting upon the ledge 11 and the support 12 with a projecting hook 18 extending under the ledge 11. They are each provided with a corresponding rear web portion 19, terminating in an outer portion 20 in supporting engagement with the ledge 14. Thus, each of the bars are individually and independently supported in assembly to form with the baffles a complete enclosed fuel retaining and supporting tuyère.

Each bar has its fuel supporting surface indicated at 21, formed with inwardly tapering walls terminating at the cored opening indicated at 23. Spaced at intervals along the tapered walls 22 there are cast lugs 24 with their side surfaces extending perpendicularly to the fuel supporting face 21, and extending inwardly partially to the opening 23. The outer face of each of the lugs is slightly spaced outwardly from the corresponding edge of the face of the bar so that such edge is in effect slightly raised therebetween.

In between each adjacent bar there is sandwiched a baffle 16, the web portion 19a of this baffle lying against and embraced by opposed lugs 24 of the bar, wherefore the web portion 19a of the baffle is slightly spaced from the adjacent edges of the fuel supporting surface 21 to permit air to escape therebetween.

The outer portion of the baffles is formed with a baffling flange 25, being substantially T-shape in cross section in association with the web portion 19a. The exposed inner surfaces of the baffling flange 25 is notched or serrated as indicated at 26, the serrations bearing directly against opposed side portions of the opposed face on the bars, as shown in Figs. 2 and 3. However, the lower portion of the baffles, that portion which extends upwardly from the retort, may preferably have one side thereof chamfered, as indicated at 27. At the forward end of the baffle there is a base portion 17a adapted to rest upon the ledge 11 and the support 12, said base portion being provided with a projecting hook 18a arranged to extend under the ledge 11. Extending rearwardly from the base portion 17a there is a web portion 19a terminating in an outer and downwardly extending tongue portion 20a, said tongue portion being arranged for supporting engagement with the ledge 14. Thus, each of the baffles is individually and independently supported in assembly to form with their associated and corresponding bars 15 a complete, enclosed fuel retaining and supporting tuyère.

By reason of this tuyère construction, as the fuel rises to the combustion area of the fuel bed, within the confines of the bars, air is gently introduced evenly about the combustion area by reason of its forced passage from the wind box surrounding the tuyère between the spaced lugs 24 of the bars through the elongated slot provided by the slight spacing between the bars and the web portion of the baffles. As it passes therebetween it is trapped within the several serrations 26 so as to be pocketed thereby before reaching the fuel. The only escape, therefore, is laterally from between the serrations into the fuel bed, each serra-

tion acting as an independent air nozzle laterally directed. By this means the air is distributed and prevented from channelling the fuel so that excess blasts of air are localized.

5 The air is not only prevented from developing spotty blasts, such as to form clinkers, but is distributed by the multiplicity of serrations which in effect provide laterally directed air nozzles. Additionally, the baffling flange 25 provides a supporting surface for the fuel as well as a portion 10 of the surface 21 of the bars 15. The overlapping character of the supporting surfaces, coupled with their protection of the laterally directed air openings, prevents siftings of the fuel particles from 15 having any tendency to fall through or into the air openings or ducts. Consequently there is no plugging up of the air openings, so that distribution of the air supply remains constant throughout the entire fuel supporting surface of the tuyère. As illustrated in Fig. 1, the angularly extending supporting portions 20 of the tuyère bars and flanges are held in place on the ledge 14 20 by refractory material being lapped thereover in such manner as to prevent their dislocation while 25 the fire is being cleaned.

As it is desirable to introduce more air to the outer portions of the tuyère than to the faster burning central portions thereof, the serrations are so formed on the baffle flanges as to control 30 the air distribution over the surface of the tuyère to admit more air over the outer portions than the inner portions, as in Fig. 4. It may be noted that for this purpose the serrations are formed of progressively less width from the outer to the inner 35 portions of the tuyère.

In the modified form of the invention shown in Figs. 7 to 11, inclusive, the same principle of construction is illustrated as applied to a circular tuyère wherein the retort 10 supports a 40 series of concentric rings 110a, and from which the retort casing 113 extends upwardly and outwardly to provide an annular support 114, the air from the forced draft being directed into the tuyère. Supported about the periphery of the 45 top ring 110a there is a series of bars 115, each extending upwardly and outwardly in a vertical radial plane through the center of the tuyère. Said bars flare outwardly and upwardly to conform with the flared formation of the tuyère 50 structure, their upper ends being supported on the annular support 114.

Supported intermediate each of said bars, there 55 is a baffle 116 similarly supported at its lower end on the top ring 110a and at its upper end on the support 114. For this purpose the lower end of the baffle is notched at 117a and provided with a lip 118a to interlock with the top ring, and at the other end is formed with a downwardly extending lug 120a to interlock with a groove formed 60 in the support 114. The inner portion of the baffle is flanged at 125 to partially overlap the adjacent exposed surfaces of the bars 115 so that the fuel supporting surface of the tuyère comprises alternately the flange 125 and the intermediate exposed surface of the bar 115.

The bars and baffles may be spaced laterally 70 relative to each other by any suitable means or by their formation, there being herein illustrated a projection 124 formed on the bars to space them from the lower portion of the baffles, coupled with a head 124a of greater width to effect the spacing thereof from the upper end. This is to permit the passage of air between the adjacent portions of the bars and baffles.

75 The underside of the flange 125 is formed with

a plurality of serrations or inwardly extending projections 126 which act to space the overlapping flange from the fuel supporting surface of the bars so that the air may pass therebetween to the fuel. As above discussed, the serrations 126 cause the air to be diffused and localized so as to discharge as from a plurality of laterally directed nozzles throughout and about the entire area of the fuel bed.

The invention claimed is:

1. A tuyère construction for solid fuel underfeed stokers, including a retort through which the fuel is fed upwardly, a tuyère bar supporting frame extending outwardly therefrom, a plurality of tuyère bars supported to extend upwardly and outwardly upon said frame about the upper portion of said retort, each of said bars being disposed to an air chamber and having a fuel supporting surface with a web portion formed with inwardly inclined surfaces, a baffle T-shaped in cross section having a web portion thereof supported on said frame between each of said bars and having a baffling flange partially overlapping said bars to jointly present therewith a fuel supporting surface, spacing lugs on opposite surfaces of each bar web portion to engage and space the web portion of said baffle laterally therefrom for air admission and distribution therebetween, and a series of serrations formed inwardly of said flange to diffuse and direct the air laterally over the fuel supporting surfaces of said bars, the effective openings provided by said serrations decreasing from the outer to the inner portions of the tuyère to admit more air to that portion of the tuyère on which the fuel may normally burn more slowly than that portion on which the fuel may normally burn faster.

2. A tuyère construction for supporting a fire bed of solid fuel adapted to admit and diffuse air while preventing siftings of the fuel therethrough, comprising a support conforming thereto, a series

of tuyère bars individually supported by said support to extend upwardly and outwardly, each of said bars including a web portion having a thickened section adjacent its outer periphery, a series of baffles supported between each of said bars, said baffles being flanged to conform to and overlap the adjacent portions of the respective bars to jointly therewith provide a fuel supporting surface, a plurality of spaced projections on each side of said bars for spacing said bars and said baffles laterally relative to each other to provide air spaces therebetween, each of said air spaces being constricted by said thickened section, and a series of spaced projections between said bars and the flanges of said baffles, the spaces between said projections forming passages to permit passage of the air while diffusing and directing the air laterally to the fuel.
